PROCESS OF MAKING TETRA-ALKYL LEAD.

No Drawing.

Application filed October 15, 1927. Serial No. 226,514.

This invention relates to an improvement in the production of tetra-alkyl lead, and more particularly to the production of such a compound by the action of alkyl chlorides on sodium lead alloys.

A process for producing tetra-alkyl lead by the action of alkyl chlorides on sodium lead alloys at temperatures above the normal boiling point of the alkyl chloride has previously been disclosed. It has been found, however, that with large scale operations it is impossible to control the reaction when all of the components are mixed at one time. A procedure has also been disclosed in which the accompanying excess temperatures and pressures are avoided by progressively adding the alkyl chloride to the alloy under agitation in an autoclave.

In a copending application of H. W. Daudt, Serial No. 226,529, filed October 15, 1927, one of us has disclosed a process recently developed in which the components are caused to react at atmospheric pressure and at temperatures at or below the refluxing temperature of the reaction mass.

An object of our present invention is to more closely control the temperature and pressure conditions by having more liquid present during the greater part of the reaction. This object has been accomplished by the development of a procedure involving the progressive addition of the alloy to the alkyl chloride, the latter being held at a definite temperature in an autoclave. The success of this procedure has depended upon the ability to feed the alloy to the alkyl chloride with the whole system under the same pressure. This step has, in turn, been accomplished by means of a new departure, that of maintaining the alloy hopper at such a temperature that any alkyl chloride contained therein, reacts very slowly, if at all, with the alloy. This may be accomplished by maintaining the hopper at a very low temperature. We prefer, however, to heat the hopper to a temperature such that any alkyl chloride contained therein is entirely converted to the vapor phase. Preferably a temperature difference of approximately 50° C. is maintained between the hopper and the autoclave. The exact difference is, however, of little importance, the conditions to be complied with being merely that substan-

tially no liquid alkyl chloride shall be present in the hopper, and that the temperature of the latter shall not be raised so high as to produce destructive reaction between the alloy and the alkyl chloride. In this condition the alkyl chloride reacts very slowly, if at all, with the alloy. The high temperature of the alloy is maintained by surrounding the hopper with a steam jacket. The alloy may be fed from the hopper by means of a worm feed, or other suitable means.

Unless precautions are observed to prevent the action of the alkyl chloride on the alloy in the hopper, the process would be inoperative, for the reason that the alloy would become spongy and it would be impossible to feed it in a satisfactory manner.

In the procedures given below as examples of our invention, the following equipment may be used:

A steam jacketed hopper is attached to a water jacketed autoclave, which is provided with the usual stirring equipment, pressure gauge and safety release valves. The hopper is provided with a worm feed by means of which the alloy is fed into the autoclave.

Example A.

Place 2000 parts of alloy, containing approximately 10% sodium and 90% lead, in the hopper; tighten the cover securely, and turn on 15-20 lbs. steam in the jacket. Feed 1800 parts of ethyl chloride into the autoclave, and, after closing all valves, raise its temperature to 70° C. While maintaining this temperature, gradually add the alloy over a period of 2-4 hours. Subsequently, maintain the same temperature for 4 hours.

Cool the charge to 30° C. and distill the excess ethyl chloride into suitable condensing equipment, by means of which it may be recovered.

Drown the charge in 3000 parts of water and recover the tetra-ethyl lead by steam distillation in the usual manner.

Example B.

Place 2000 parts of alloy containing approximately 10% sodium and 90% lead in the hopper, tighten cover securely, and turn on 15-20 lbs. of steam into the jacket. Feed 800 parts of kerosene and 560 parts of ethyl

chloride into the autoclave, and, after closing all valves, raise the temperature to 80° C. While maintaining this temperature, gradually add the alloy over a period of 2-3 hours; subsequently hold this temperature for 4 hours.

Cool the charge to 20-25° C. and extract the tetra-ethyl lead with gasoline.

While we have described the process as 10 specifically applied to the preparation of tetra-ethyl lead, it is applicable as well to the preparation of other tetra-alkyl lead compounds from the corresponding alkyl chlorides.

15 Although the alloy which we prefer to use is the 10% sodium alloy which has been known to give the best results in processes heretofore disclosed, the procedure disclosed by us is also applicable to the use of other 20 alloys of lead and sodium.

Our procedure is also applicable to the pressureless process described in copending application of H. W. Daudt, Serial No. 226,- 529, filed October 15, 1927.

25 For this latter process the use of alloys containing potassium, sodium and lead is particularly advantageous.

The use of solvents, as described in Example B, is of advantage in that it reduces 30 the pressure and allows the use of much smaller amounts of ethyl chloride. Benzene and toluene have also been used to advantage. Also any inert solvent with a low vapor pressure may be used.

35 The reaction with the sodium lead alloy will start at temperatures as low as 35° C., and favorable results may be obtained with temperatures as high as 110° C., but we have found that temperatures of 50° C. to 100° C. 40 are most satisfactory and these limits may be used with small variation in yield. To go much below 50° C. there is danger of delayed reaction.

We have also found that with the use of the 45 potassium bearing alloys temperatures as low as 20° C. can be advantageously used.

Our process has a number of distinct advantages over processes previously known. In our process, the whole operation can be 50 run at one definite temperature. We find that we can run an entire charge with a variation of less than 2° in temperature and of 5 lbs. in pressure. With processes heretofore known this is impossible. Without the 55 use of solvents the pressure is approximately the same as the average of those obtained in normal runs by the older process. With the use of solvents this pressure can be reduced from the approximately 60-90 lbs. To approximately 30-50 lbs. at the temperatures usually employed.

The use of a solvent is desirable in our process, but in processes of the prior art it may be dangerous, because the building up of 60 a high enough concentration of ethyl chlo-

ride for the starting of the reaction may result in an uncontrollable reaction.

With the use of solvents in our process it is possible to materially cut down the amount of ethyl chloride usually required.

Our new process gives higher yields than the processes heretofore known.

As many apparently widely different embodiments of this invention may be made without departing from the spirit thereof, it 75 is to be understood that we do not intend to limit ourselves to the specific embodiments thereof except as indicated in the appended claims.

We claim:

1. In the process of making tetra-alkyl lead from a lead alkali metal alloy and an alkyl chloride, the improvement which comprises the progressive addition of the alloy to the alkyl chloride.

2. In the process of making tetra-alkyl lead from a lead alkali metal alloy and an alkyl chloride, the improvement which comprises the progressive addition of the alloy to the alkyl chloride, under such conditions that the rate of addition of the alloy is the primary factor in determining the progress of the reaction.

3. In the process of making tetra-alkyl lead by the reaction between a lead alkali metal alloy and an alkyl chloride at substantially atmospheric pressure, the improvement which comprises the progressive addition of the alloy to the alkyl chloride, under such conditions that the rate of addition of the alloy is the primary factor in determining the progress of the reaction.

4. In the process of making tetra-alkyl lead by the reaction between a lead alkali metal alloy and an alkyl chloride at elevated pressures, the improvement which comprises the progressive addition of the alloy to the alkyl chloride, under such conditions that the rate of addition of the alloy is the primary factor in determining the progress of the reaction.

5. In the process of making tetra-alkyl lead from a lead alkali metal alloy and an alkyl chloride, the improvement which comprises the progressive addition of the alloy to the alkyl chloride, the alloy being fed from a hopper wherein it is maintained under such temperature conditions that substantially no reaction takes place between it and any alkyl chloride which may be present in the hopper.

6. In the process of making tetra-alkyl lead by the reaction between a lead alkali metal alloy and an alkyl chloride under pressure, the improvement which comprises the progressive addition of the alloy to the alkyl chloride, the alloy being fed from a hopper wherein it is maintained under such temperature conditions that little or no reaction takes place between it and any alkyl chloride which may be present in the hopper.

7. In the process of making tetra-alkyl lead from a lead alkali metal alloy and an alkyl chloride, the improvement which comprises the progressive addition of the alloy to the alkyl chloride, the alloy being fed from a hopper which is maintained at such a temperature that any alkyl chloride contained therein is substantially all converted to the vapor phase. 70
- 13 8. In the process of making tetra-alkyl lead by the reaction between a lead alkali metal alloy and an alkyl chloride under pressure, the improvement which comprises the progressive addition of the alloy to the alkyl chloride, the alloy being fed from a hopper which is maintained at such a temperature that any alkyl chloride contained therein is substantially all converted to the vapor phase. 75
- 15 9. In the process of making tetra-alkyl lead from a lead alkali metal alloy and an alkyl chloride in the presence of a diluent, the improvement which comprises the progressive addition of the alloy to the alkyl chloride. 80
- 20 10. In the process of making tetra-alkyl lead from a lead alkali metal alloy and an alkyl chloride in the presence of a diluent, the improvement which comprises the progressive addition of the alloy to the alkyl chloride, the alloy being fed from a hopper which is maintained at such a temperature that any alkyl chloride contained therein is substantially all converted to the vapor phase. 85
- 30 11. In the process of making tetra-ethyl lead from a lead alkali metal alloy and ethyl chloride, the improvement which comprises the progressive addition of the alloy to the ethyl chloride. 90
- 35 12. In the process of making tetra-ethyl lead from a lead alkali metal alloy and ethyl chloride, the improvement which comprises the progressive addition of the alloy to the ethyl chloride. 95
- 40 13. In the process of making tetra-ethyl lead by the reaction between a lead alkali metal alloy and ethyl chloride at substantially atmospheric pressure, the improvement which comprises the progressive addition of the alloy to the ethyl chloride under such conditions that the rate of addition of the alloy is the primary factor in determining the progress of the reaction. 100
- 45 14. In the process of making tetra-ethyl lead by the reaction between a lead alkali metal alloy and ethyl chloride at elevated pressures, the improvement which comprises the progressive addition of the alloy to the ethyl chloride under such conditions that the rate of addition of the alloy is the primary factor in determining the progress of the reaction. 105
- 50 15. In the process of making tetra-ethyl lead from a lead alkali metal alloy and ethyl chloride, the improvement which comprises the progressive addition of the alloy to the ethyl chloride, the alloy being fed from a hopper which is maintained at such a temperature that any alkyl chloride contained therein is substantially all converted to the vapor phase. 110
- 55 16. In the process of making tetra-ethyl lead by the reaction between a lead alkali metal alloy and ethyl chloride under pressure, the improvement which comprises the progressive addition of the alloy to the ethyl chloride, the alloy being fed from a hopper which is maintained at such a temperature that any ethyl chloride contained therein is substantially all converted to the vapor phase. 115
- 60 17. In the process of making tetra-ethyl lead by the reaction between a lead alkali metal alloy and ethyl chloride under pressure, the improvement which comprises the progressive addition of the alloy to the ethyl chloride, the alloy being fed from a hopper which is maintained at such a temperature that any ethyl chloride contained therein is substantially all converted to the vapor phase. 120
- 65 18. In the process of making tetra-ethyl lead from a lead alkali metal alloy and ethyl chloride, in the presence of a diluent, the improvement which comprises the progressive addition of the alloy to the ethyl chloride. 125
- 70 19. In the process of making tetra-ethyl lead from a lead alkali metal alloy and ethyl chloride, in the presence of a diluent, the improvement which comprises the progressive addition of the alloy to the ethyl chloride, the alloy being fed from a hopper which is maintained at such a temperature that any alkyl chloride contained therein is substantially all converted to the vapor phase. 130
- 75 20. In the process of making tetra-ethyl lead by the reaction between a lead alkali metal alloy and ethyl chloride under pressure, in the presence of a diluent, the improvement which comprises the progressive addition of the alloy to the ethyl chloride, the alloy being fed from a hopper which is maintained at such a temperature that any alkyl chloride contained therein is substantially all converted to the vapor phase. 135
- 80 21. In the process of making tetra-ethyl lead from a lead-sodium alloy and ethyl chloride, the improvement which comprises the progressive addition of the alloy to the ethyl chloride. 140
- 85 22. In the process of making tetra-ethyl lead from an alloy of lead, sodium, and potassium, and ethyl chloride, the improvement which comprises the progressive addition of the alloy to the ethyl chloride. 145
- 90 23. In the process of making tetra-ethyl lead by the reaction between a lead-sodium alloy and ethyl chloride, under pressure, the improvement which comprises the progressive addition of the alloy to the ethyl chloride, the alloy being fed from a hopper which is main-

tained at such a temperature that any ethyl chloride contained therein is substantially all converted to the vapor phase.

24. In the process of making tetra-ethyl lead from a lead-sodium alloy and ethyl chloride in the presence of a diluent, the improvement which comprises the progressive addition of the alloy to the ethyl chloride.

25. In the process of making tetra-ethyl

lead from an alloy of lead, sodium and potassium, and ethyl chloride, in the presence of a diluent, the improvement which comprises the progressive addition of the alloy to the ethyl chloride.

In testimony whereof we affix our signatures.
